UNITED STATES PATENT OFFICE.

ROYAL L. BOULTER, OF LOS ANGELES, CALIFORNIA.

RAZOR-BLADE HOLDER.

1,293,319.

Specification of Letters Patent.

Patented Feb. 4, 1919.

Application filed November 20, 1916. Serial No. 132,257.

To all whom it may concern:

Be it known that I, ROYAL L. BOULTER, a citizen of the United States, residing at Los Angeles, in the county of Los Angeles and State of California, have invented certain new and useful Improvements in Razor-Blade Holders, of which the following is a specification.

This invention relates to improvements in 10 razor devices, and particularly to razor blade holders adapted to receive and hold razor blades of different kinds and styles in position for use. The device is especially designed to afford a holder for razor blades of 15 the safety type.

It is an object of the invention to provide a simple economical razor blade holder having an adjustable razor blade support, whereby blades of different widths and kinds may 20 be adjustably held for exposing the proper amount of cutting edge for use in shaving.

It is also an object of the invention to provide a razor blade holder having equalizing clamping jaws for holding the blades in the 25 shaving position.

It is a further object of the invention to produce a razor blade holder of the safety type having razor blade engaging and holding jaws, and a spring for movably keeping 30 them in razor gripping position, the said spring also operating as a safety guard for preventing the user of the razor from accidentally cutting himself.

It is still a further object of the invention 35 to provide a razor blade holder having an integral handle with razor blade back support, having an adjustable member for controlling the amount of projection of blade, and having pivoted spring actuated 40 blade jaws for removably clamping the razor blade in place.

With these and other objects in view, the invention comprises certain novel constructions, combinations and arrangements of 45 parts, as will be hereinafter more fully described and claimed.

In the accompanying drawing forming a part of this specification:

Figure 1 is a side elevation of a razor blade 50 holder, constructed in accordance with the present invention.

Fig. 2 is a top plan view of the same, the razor gripping jaws being in their normal blade gripping positions.

55 Fig. 3 is a detail top plan view of the blade carrying portion of the holder, the

razor holding members or jaws being retracted and the blade removed.

Fig. 4 is a central sectional view taken axially of the blade holding portion of the 60 device.

Fig. 5 is a sectional view taken upon the line 5—5 of Fig. 4.

Fig. 6 is an end elevation of a razor holder looking at the razor backing and supporting 65 end of the device.

The razor blade holder forming the subject matter of this invention is designed to afford one in which many different kinds of 70 razor blades may be interchangeably employed, the width or shape of the blade not interfering with the holding of the same in shaving position.

The details and features of a preferred 75 form of the said holder will now be more specifically described, reference being had to the accompanying drawing, in which 6 indicates a handle having a broad end portion bent and shaped to receive and adjustably hold a razor blade 7. The blade holding and 80 adjusting means is preferably mounted between substantially parallel portions 8 and 9 of the broad end of the handle, said parts being connected by a transverse portion 10. The portion 9 is made broader and deeper 85 than the portion 8 for offering a broad ample support for the razor blade 7. The handle and the parts 8, 9, and 10 forming bent extensions thereof may be made of comparatively thin material, having the lateral edges 90 thereof bent at right angles thereto, to form strengthening flanges 11, 12, 13 and 14, whereby the requisite stiffness may be given to the frame of the device.

The central portion of the part 8 and the 95 handle adjacent thereto, is preferably cut away, and a portion of the cut-out material is bent to form a tongue 15, which is brought to a plane approximately parallel with the plane of the portion 10. A screw 16 is 100 mounted in the free end of the tongue 15, and in the portion 10, so that the said screw is substantially parallel with the body portion of the part 9. A flanged nut 17 is threaded upon said screw, the flanges thereof affording 105 a groove 18, in which fits a socket portion 19 formed upon an adjustable blade supporting bar 20. The flanges of the nut 17 are usually knurled or serrated upon the edges thereof as at 21 to facilitate the turning of 110 the nut in adjusting the same upon the screw 16. The long edge of the bar 20 bears

against the surface of the blade supporting back portion 9, whereby it is movably held in position with respect to the adjusting nut 17. Projections 22 are formed upon the long 5 edge of the said bar 20, and project through slots 23 formed in the portion 9, whereby the bar is guided in its adjustment along the screw. A razor blade resting upon the bar 20 can thus be adjusted, so that its cutting 10 edge will be caused to project a proper distance above the portion 9.

Means for clamping and gripping the blades in position is preferably arranged upon the screw 16 adjacent to the tongue 15. 15 The means shown in the illustration comprises a pair of angular shaped jaws 24 and 25, having operating arms 26 and 27, projecting from the outer ends thereof, approximating at right angles thereto, as clearly 20 shown in Figs. 2 and 3 of the drawing.

The blade engaging portions of the jaws are provided with bearing edges 28, which extend parallel to the portion 9, and the blade resting against the same. The jaws 25 are adapted to be movably drawn against the blade or the portion 9 behind the same by a spring 29, the ends of which are secured to projections 30 formed at the outer ends of the jaws 24 and 25. The said projections 30 may be stamped outwardly from the ends of the jaws, and bent upon themselves as shown in Figs. 1 and 4, the said projections having a series of perforations 31 therein through which several turns of the 35 spring 29 are placed for fastening the said spring to the said jaws.

The spring may be readily put in place by turning the same until the ends thereof have been threaded through the apertures 31 40 as indicated in the drawing. The spring is so located that its line of pull upon the outer ends of the jaws comes between the axis of the spring 16 and the portion 9, whereby the jaws will normally be pulled in blade holding 45 positions.

It will be evident by reference to Fig. 3 of the drawing, that by pressing upon the outer ends of the arms 26 and 27, simultaneously, the jaws 24 and 25 will be retracted from 50 their engagement with the razor blade, at which time the blade may be removed and a new one inserted. A nut 32 is applied upon the screw 16 inside the jaws, for preventing the jaws from slipping back and forth on 55 the said screw. The nut 32 is preferably provided with a hub portion 33, which is made of sufficient length to permit the nut to be tightened against the tongue 15, without interfering with the free movement of the 60 jaws 24 and 25. The head of the nut is thus spaced from the tongue 15 by the said hub for a distance a little greater than the thickness of the two jaws 24 and 25.

The projections 30 which support the spring 65 29, are carried outwardly sufficiently to hold

said spring near the edge of the razor blade, thus permitting the spring to act as a safety guard and tend to prevent danger of cutting oneself by the use of the device. The said spring has thus a double function, of a blade 70 guard, and a jaw actuating means.

As shown in Fig. 6 of the drawing the body portion of the part 9 is preferably cut away at 34, a sufficient distance to properly expose enough of the razor blade to permit 75 of the shaving operation.

In connection with the blade supporting bar 20, the socket portion 19 is made with its forked part sufficiently elongated as at 80 35, to have an ample bearing in the groove 18 to prevent the said bar 20 from tipping, and thus to keep it substantially parallel with the portion 10 of the holder. The projections 22 in addition to acting as guides for the bar 20, also perform an important 85 function in supporting very thin razor blades, for said projections preventing any possibility of the blade slipping down between the edge of the bar 20 and the portion 9 of the handle, as will be readily understood. Without such projections this might happen with any thin blades, and especially such as are sharpened on both edges.

It will be evident that the razor blade 95 holder above described is of simple construction and capable of economical production, and that it is readily adaptable for the use of any kind of a razor blade of the style employed in a safety razor structure.

It will be evident that the bar 20 can be quickly adjusted for blades of any width, and that the gripping jaws afford a quickly operating mechanism for gripping or releasing a blade. The mounting of the two 105 jaws, adapted to be brought together by the spring 29, gives an equalizing effect, whereby each jaw exerts substantially the same pressure upon the blade as the other jaw. The spring need not be very stiff, or of great 110 strength to hold the razor blade properly for shaving, especially as the jaw 20 positively supports the razor blade in true position, with respect to the upper edge of the portion 9, and the guard formed by the spring 29. 115

It will be evident that the minor details of construction may be somewhat altered within the scope of the invention, and that mechanical equivalents may be substituted for some of the parts, without departing in 120 the least from the spirit of said invention.

In employing a spring guard as above shown and described, it will be observed that such a guard has a slight yielding quality when pressed against the face, so that the 125 blade becomes more prominent and thus performs the shaving operation more readily, especially upon uneven portions of the face.

What is claimed is:

1. A razor blade holder comprising a 130

- member adapted to receive a razor blade flatwise thereagainst, an adjustable supporting member at right angles thereto, and adapted to support said razor blade edgewise thereupon, spring actuated holding members adapted to bear yieldingly against the opposite side of said razor blade, whereby to press it against the member at the opposite side thereof, and a guard member 10 mounted adjacent the cutting edge of said razor blade.
2. A razor blade holder comprising a blade holding means, a pair of clamping members, a spring yieldingly holding said 15 clamping members against said blade, said spring being positioned adjacent the cutting edge of said blade, whereby to act as a guard therefor, and means for adjustably holding said blade edgewise.
- 20 3. A razor blade holder comprising a blade holding means, a pair of blade clamping jaws, a spring for drawing said jaws toward each other, whereby they will press upon the blade for holding it in place, and 25 oppositely projecting handles connected with the said blades, the structure being such that pressure upon said handles will move the jaws to release the blade.
4. A razor blade holder having a blade 30 holding means, clamping jaws for the blade, a spring for actuating said jaws, the said spring being arranged adjacent to the blade held by the holder, whereby it acts as a safety guard.
- 35 5. A razor blade holder comprising an integral handle and frame portion adapted to receive and support a razor blade, an adjustable bar for receiving the blade and holding it with respect to the said frame, a 40 screw standard, a flanged nut thereon adapted to movably support the said blade bar, and clamping jaws adapted to bear upon the blade near its cutting edge for holding it in shaving position.
- 45 6. A razor blade holder comprising a blade support, a blade adjusting bar having interfitting engagement with said blade support, and movable therealong, and adapted to support a blade edgewise, spring actuated 50 holding members adapted to bear against said blade, whereby to press it against said blade support at the opposite side thereof, and a spring for operating said holding members, substantially as described.
7. A razor blade holder comprising an integral handle, having one end thereof bent to form a blade backing support, a screw member mounted in said bent portion, a tongue struck out of said handle for bracing said screw member in place, blade clamping 55 jaws mounted upon said screw member, a blade adjusting support engaging said screw member, and a combined guard and spring carried by the said jaws.
8. A razor blade holder comprising a handle and frame portion, an adjustable support for a razor blade, pivoted jaws for clamping the blade in position, said jaws having projections thereon extending adjacent to the cutting edges of the blade, a 60 spring fastened to and connecting the said projections, whereby the spring is held adjacent to the cutting edge of the blade for acting as a safety guard, and the jaws are 65 carried to clamp the blade in place.
9. A safety razor structure comprising a holding member, a razor blade adjustable therein, a blade supporting bar, having a bifurcated projection, an adjusting member 70 engaging the said bifurcated projection, and a screw member engaging said adjusting member, whereby the blade may be caused to project at its cutting edge, a proper distance for shaving purposes.
10. In a device of the character referred 75 to, razor blade holding members, a coiled spring operating thereon, whereby to yieldingly hold said blade in operating position, said spring being positioned to operate also as a safety guard adjacent the cutting edge 80 of said blade.
11. In a device of the character referred 85 to, a blade holding member adapted to receive a blade flatwise thereagainst, an adjustable holding member for supporting said 90 blade edgewise, adjustable holding means for pressing said blade flatwise against the holding member at the opposite side thereof, and a coiled spring mounted adjacent the cutting edge of said blade to operate as a 95 safety guard, substantially as described.
- In testimony whereof, I have hereunto set my hand, in presence of two witnesses.

ROYAL L. BOULTER.
